THREAD PARTER FOR WEFT REPLENISHING LOOMS

Application filed February 21, 1931. Serial No. 517,559.

This invention relates to improvements in thread parters for looms and it is the general object of the invention to provide a simplified device of this nature which shall act to sever the thread at the eye end of the shuttle, preferably by advance movement of the shuttle.

In weft replenishing looms there usually remains at the time of transfer a weft end 10 which extends from the selvage along the front shuttle wall to the weft delivery eye, through the latter and down through the bobbin slot in the lay to the bobbin can. Unless this weft end is extracted prior to the 15 pick immediately following transfer there is a likelihood that it will be whipped into the shed to form an imperfection in the cloth. It has been proposed heretofore to cut the end at the shuttle feeler, clamping 20 that part which extends toward the selvage and releasing the portion which extends toward the delivery eye, and depending upon some additional mechanism to withdraw this latter portion. It is an important object of 25 my present invention to part the filling adjacent the delivery eye and clamp the thread at some point intermediate the eye and the selvage, such as at the shuttle feeler. In this way it is necessary to deal with but one end, 30 the part extending beyond the shuttle eye being extracted by the expelled bobbin.

It is a further object of my present invention to provide a cutter or thread parter which shall reside in part in a plate or anvil 35 on the shuttle and in part in a movable weft parting edge which is brought into contact with the anvil preferably at the time of transfer. The anvil is carried by the front wall of the shuttle and disposed so as to extend across the weft end which usually extends longitudinally in alignment with the front delivery eye. In this connection I find it convenient to control the cutting edge 40 through the transferring mechanism by a connection which normally holds the cutter out of contacting position with respect to the anvil but acts when the transference arm descends to permit the cutting edge to move rearwardly toward the anvil. In this way 45 the cutting elements move toward each other

and the cutting is accomplished by a motion which is faster than that of the lay alone.

In multicolor weft replenishing mechanisms it is customary to locate the weft detector under the magazine where it may enter a slot in the front wall of the shuttle to detect the presence of weft. When the thread controlling mechanism set forth herein is employed it is desirable to insure a free path of 55 movement for that part of the weft which extends from the shuttle eye to the thread clamp. If the detector is not retracted sufficiently removal of this part of the thread may be rendered difficult by entanglement 60 with the feeler finger. This is particularly true with high twist yarns. It is accordingly another object of my invention to control the thread cutter and detector in such a way that when the cutter acts to release the thread 65 at the shuttle eye the feeler will be moved forwardly to a point where it cannot interfere with that part of the weft which may tend to snap from the eye toward the shuttle 70 feeler clamp. It is desirable to accomplish 75 this result whether the binder be on the front with a shuttle carried groove for the weft or whether the binder be on the back and the front wall of the shuttle box engages only the 80 upper part of the shuttle.

Another object of my invention is to arrange the cutter so that two coacting parts will have relative sliding motions, either vertically or horizontally, to assist in parting the weft, the relative motion being produced by a 85 force derived from the shuttle and transmitted preferably through the anvil.

It is a still further object of the invention to provide a cutter or parter which will be dependent for its operation upon the actual 90 presence in proper position of the shuttle, preferably the shuttle eye, before a cutting operation can occur.

Still another object of the invention is to rely upon pinching the weft between a parting edge and a relatively hard surface. The latter may be of a form such that it can be thought of as having been generated by the 95 parting edge.

With these and other objects in view which 100

will appear as the description proceeds, my invention resides in the combination and arrangement of parts hereinafter described and set forth in the claims.

5 In the accompanying drawings, wherein a convenient embodiment of my invention is set forth,

10 Fig. 1 is a top plan view showing a portion of a loom equipped with my present invention, the parts being in thread parting position and the detector withdrawn,

Fig. 2 is a vertical section on line 2—2 of Fig. 1,

15 Fig. 3 is a front elevation of a shuttle which comprises a portion of my present invention,

Fig. 4 is an enlarged elevation of a portion of Fig. 2, certain parts being in section,

10 Fig. 5 is a vertical section on line 5—5, Fig. 1, showing the parts in operating position,

20 Fig. 6 is a view similar to Fig. 5 but with the parts in a different position, and

Fig. 7 is a view looking in the direction of arrows 7—7, Fig. 6.

Referring to Fig. 1, I have shown a breast beam 10 and a lay 11 pivoted at L, see Fig. 6. Front and rear walls 12 and 13, respectively, define the shuttle box for a shuttle S.

30 As set forth herein the front wall is stationary with respect to the lay and is formed to expose the lower front part of the shuttle, while the rear wall is formed in part by a yielding binder 14. A loom frame 15 supports a multi-color weft replenishing mechanism 16 which may operate as shown in Patent No. 1,030,748.

35 This mechanism comprises a fixed stud 17 on which is pivotally mounted a transerrer arm 18 having a hub 19. The latter has a pair of depending legs 20 between which is pivoted a latch holder 21 carrying a latch 22. The latch can be raised by appropriate mechanism into the path of bunter 23 on the lay for the purpose of depressing the transerrer arm 18.

40 Any form of weft detector may be used, that form shown herein being designated generally at D and comprising a rearwardly extending feeler finger 24 pivotally mounted on a slide 25 the forward end of which is upturned as at 26. The detector of itself may be as shown in my prior Patent No. 1,738,198

50 and forms no part of my present invention, although the control therefore is a feature of this invention. It is sufficient for present purposes to say that the detector and slide 25 will move forwardly without angular

55 movement when a working supply of weft is present, but when exhaustion approaches the finger will move angularly about its slide carried pivot and along a denuded bobbin to initiate a subsequent depression of the transerrer lever for the purpose of effecting a change of bobbins in the active shuttle.

60 As shown in Figs. 5 and 6, the clamp which I use may be mounted on a shuttle feeler of the type shown in Patent No. 1,261,417 and comprises a stand 27 to which is pivoted a

lever 28. The latter is connected to a link 29 which is raised when a transfer is to occur. A shuttle feeler arm 30 is pivoted to the lever and is resiliently held in normal position by a compression spring 31, stop surfaces 32 and 33 on the lever and arm, respectively, limiting movement of the latter. A clamping jaw 34 is pivoted to the arm and is attached to an operating rod 35 guided in a swivel 36 on the stand 27. A spring 37 between the swivel and a collar 38 on the rod permits a limited yielding of the rod. Stop nut 39 on the rod engages the top of the swivel and acts to open the jaw when the link 29 is raised. Forward movement of the shuttle feeler by engagement with the lay, as seen in Fig. 5, operates to close the jaw and reset the magazine, although this latter result need not be accomplished by the shuttle feeler. Forward motion of the shuttle feeler caused by a misplaced shuttle will prevent transfer.

65 The mechanism thus far described is of common construction, being substantially the same as that found in the ordinary well-known stationary magazine loom and in the aforesaid patents.

70 In carrying my invention into effect I provide two separate thread parting members which are brought into coaction at the desired time. The first member consists of a hard or metallic plate 40 which, as shown in Fig. 3, may be set slightly into the front wall of the shuttle and extend both above and below the delivery eye 41. Where a thread groove 42 extends longitudinally along the front surface of the shuttle it will be interrupted by the plate. The plate is very close to the delivery eye and may be held in position on the shuttle by any approved means.

75 The second member C is mounted independently of the shuttle. A bracket 50 on the loomside carries a stand 51 which is adjustably mounted both for vertical and horizontal positioning on the bracket. An upwardly extending stud 52 on the stand, pivotally supports a cutter lever 53 the hub of which is surrounded by a torsion spring 54 having such relation with the stand and lever as normally to urge said lever in a counter-clockwise direction as viewed in Fig. 1. The effect of the spring is to move the member C rearwardly.

80 A cylindrical rod 55 is mounted for longitudinal and rotational adjustment in hub 56 formed on the right hand end of the lever 53, the setting being retained by a screw. The rear end of the rod is bifurcated as at 57 and has loosely mounted for limited vertical movement therein the cutter member C the rear end of which may be provided with a knife edge 58. The latter extends above and below a horizontal line passing through the delivery eye 41, and as suggested in Fig. 4,

the pivot 59 for the cutter blade is so placed with respect to the forward end of the bifurcation as to allow a limited angular movement in a vertical plane on the part of the plate.

5 The left hand arm 60 of the lever extends behind a depending finger 61 cast integral with the hub 19 of the transerrer arm. The spring 54 holds this arm 60 against the finger, but the transerrer arm is not moved by the spring because the position thereof is determined by a relatively heavy torsion spring 62 surrounding the stud 17. These two torsional springs oppose each other, the 15 spring 62 being strong enough to overpower spring 54. The finger 61 is so placed as to engage the upturned end 26 of the slide 25 at the time of transfer to move the feeler finger 24 forwardly away from the front 20 wall of the shuttle.

While the thread clamp which I employ near the inner end of the shuttle may be placed as set forth in the aforesaid Patent No. 1,261,417, yet it differs from that patent in that it has no cutter. The jaw 34 moves angularly between two clamping elements on the arm 30. One of these elements 70 is guided on pins 71 carried by the arm and is held against the jaw by a leaf spring 72 anchored to the arm. The other clamping element 73 may be formed as part of the arm. While I have shown two different clamp elements 70 and 73 to coact with the jaw, yet one will suffice.

35 In operation, so long as a working supply of weft is present, the feeler will move forwardly on detecting beats and will return without calling for a change. When weft is depleted, however, a change is called for which involves raising the latch 22 into the path of the bunter 23 by lifter rod 80. At the same time the clamp moves rearwardly to the position shown in Fig. 6 with the jaw in open position to define a thread receiving notch with the clamping elements. Under these conditions, and while the bunter is still out of contact with the latch, the lever 53 is held with its right hand end forward because of engagement with the finger 61.

50 As the lay advances, engagement of the bunter and latch will depress the transerrer arm, at which time the finger 61 will move forwardly. This action accomplishes two results, namely, spring 54 is permitted to move the cutter C rearwardly, and the feeler D is moved forwardly. As the cutter member C moves toward the advancing shuttle it will be approximately in the position shown in Fig. 4 with the cutting edge 58 slightly inclined. Before the lay reaches its foremost position the edge 58 will engage the plate or anvil 40 and move to the dotted line position shown in Fig. 4, to place the knife edge in contact throughout its length with the plate on the shuttle. At this time the

weft end T is extending across the plate 40 so that engagement of the latter with the edge 58 will sever the thread at a point closely adjacent to the eye of the shuttle.

As the lay swings forwardly it will turn 70 about its pivot L, but the cutter C will nevertheless be able to remain in contact with the face of plate 40 despite the changing angular position of the latter. During the forward motion of the lay subsequent to engagement 75 of the cutting members the edge 58 will slide along the plate 40 away from the clamp, thus giving additional assurance that the weft will be cut.

It is important that the clamp shall catch 80 the thread prior to the parting at the eye, and to this end the rear of the arm 30 is engaged and moved forwardly by a part of the lay early enough in the advance movement of the latter to clamp the thread at the 85 desired time.

Prior to cutting the feeler finger has been moved forwardly sufficiently so that if the thread be of a high twist and tends to snap toward the clamp the likelihood of entanglement with the feeler finger will be reduced 90 if not entirely eliminated.

It will be seen that the relative movement between the cutter blade and the shuttle wall is determined by two factors, first, the advance movement of the lay and, second, the rearward movement of the cutter C, so that the rate of cutting is greater than that of the lay.

A temple cutter 81 of any well-known construction may be employed to sever the weft end T adjacent the selvage on a subsequent pick.

From the foregoing it will be seen that I have provided a simple form of thread parter 105 which depends upon pinching the weft between a hard surface on the shuttle and a relatively sharp edge on a cutter blade, and the latter is so mounted as to align itself vertically with the shuttle surface to have contact therewith as the lay moves around its pivot. It will also be seen that the weft detector is retracted a sufficient distance to be out of the path of the weft which is released by the parter should it tend to snap back toward 110 the thread clamp. Furthermore, the thread is clamped at a point intermediate the selvage and the shuttle eye so that this entire length of weft remains intact, thereby making it necessary to manipulate but one piece of 115 thread. Again, it will be noted because of the control exercised by the finger 61 the cutter contacts with the anvil only during the act of transfer and the rate of cutting is greater than the rate of motion of the lay. Furthermore, the members may be interchanged without departing from the spirit of the invention. Also, the edge 58 slides along the plate while in contact therewith, and in this connection it is convenient to 120 125 130

think of the plate as having a surface that could have been generated by the cutting edge 58. Spring 54 yields to the lay but acts to hold the cutter members in contact with each other.

The clamp and detector need not be of the specific form set forth herein in order to carry out the spirit of certain phases of this invention.

10 Having thus described my invention it will be seen that changes and modifications may be made therein by those skilled in the art without departing from the spirit and scope of the invention and I do not wish to be limited to the details herein disclosed, but what I claim is:

1. In thread controlling mechanism for a weft replenishing loom having a shuttle from the delivery eye of which extends a weft 20 thread, an anvil carried on the front wall of the shuttle positioned to extend on opposite sides of the weft extending from the shuttle eye toward the cloth selvage, and a parter movable toward the shuttle on transferring beats of the loom to force the filling against the anvil and part the filling.

2. In a thread controlling mechanism for a weft replenishing loom having a shuttle from which weft extends, a pair of weft 30 parting members, one of which is movable forwardly by the shuttle, and means to cause said members to move into weft parting engagement with each other at a rate greater than the rate of movement of the shuttle.

3. In thread controlling mechanism for a weft replenishing loom having a shuttle from which an exhausted bobbin is expelled, a pair of coacting weft parting means, one carried by an exterior advancing surface of the 40 shuttle during transfer, and the other moving simultaneously in a direction opposite to the advance movement of the shuttle to effect parting of the weft.

4. In thread controlling mechanism for a weft replenishing loom having a shuttle from which extends a weft thread, a pair of thread parting elements one of which comprises a substantially flat hard surface on the front wall of the shuttle and the other of which 50 comprises a relatively sharp edge, and means to move said elements toward each other to pinch the filling between them, the relative rate of approach being greater than the movement of either member.

5. In thread controlling mechanism for a weft replenishing loom having a shuttle from which extends a weft thread, a pair of thread parting elements one of which comprises a substantially flat hard surface on the front 60 wall of the shuttle and the other of which comprises a relatively sharp edge, and means to move said elements toward each other to pinch the filling between them, the relative rate of approach being greater than the 65 movement of either member, both of said

members being movable forwardly with the shuttle during a portion of the transfer.

6. In thread controlling mechanism for a weft replenishing loom having a shuttle with a delivery eye from which a weft thread 70 extends, a lay to carry the shuttle forwardly, a transerrer mechanism to effect change of weft supply in the shuttle, and a pair of cooperative thread parting elements one of which is carried by the shuttle between the 75 eye and cloth and the other of which is operatively related to the transferring mechanism, and means effective when the transerrer mechanism operates to move the elements into cooperative thread parting relation.

7. In thread controlling mechanism for a weft replenishing loom having a shuttle with a delivery eye from which extends a weft thread, a lay to carry the shuttle forwardly, a transerrer mechanism movable by the lay on a forward movement thereof to effect change of weft supply in the shuttle, a pair of cooperative thread parting elements one of which is located on the shuttle 90 between the eye and cloth and the other of which is operatively related normally to the transfer mechanism, the latter effective on non-transferring picks of the loom to prevent coaction between the elements, said elements effective upon operation of transfer mechanism to have cooperative relation to part the weft on a transferring beat of the lay.

8. In thread controlling mechanism for a weft replenishing loom having a shuttle from which an exhausted bobbin is expelled, a lay to carry the shuttle forwardly during the act of transfer, a transerrer mechanism movable by the lay on a forward movement 105 thereof to effect change of weft supply in the shuttle, a lever yieldingly held against the transerrer mechanism, a thread parting element on the shuttle, a second thread parting element on the lever, the transfer mechanism on nontransferring beats of the lay holding the lever in such a position as to prevent coaction between the thread parting elements, and resilient means acting on said lever in a direction tending to effect parting 110 cooperation between the elements at all times, said resilient means normally overpowered by the transerrer mechanism but effective when the latter operates to cause cooperative thread parting action on the part 120 of the elements.

9. In thread controlling mechanism for a weft replenishing loom having a shuttle from which a weft thread extends, two coacting thread parting elements, one of said 125 elements being carried by the shuttle and so disposed as to lie along the path of the weft extending from the shuttle, the other element mounted to have a sliding movement along the first named element in a direction away 130

from the selvage of the cloth while in contact with the first named element to part the weft.

10. In thread controlling mechanism for a weft replenishing loom having a shuttle from which a weft thread extends, a pair of coacting thread parting elements one of which is carried by the shuttle, and means to move one of said elements with respect to the other in a direction away from the selvage of the cloth.

11. In thread controlling mechanism for a weft replenishing loom having a shuttle from which a weft thread extends, a pair of coacting thread parting elements one of which is carried by the shuttle, and means to move one of said elements with respect to the other in a direction away from the selvage of the cloth, while the elements are in contact with each other.

12. In thread controlling mechanism for a weft replenishing loom having a shuttle from which extends a weft thread, a lay to carry the shuttle forwardly during the act of transfer, a pair of thread parting elements one of which is carried by the shuttle, and means to cause a relative movement between the elements in the direction of the length of the shuttle as the lay advances on a transferring pick of the loom.

13. In thread controlling mechanism for a weft replenishing loom having a shuttle from which an exhausted bobbin is expelled, a lay to carry the shuttle forwardly during the act of transfer, a metallic plate carried by the front wall of the shuttle, a lever pivoted about a fixed axis and having an arm extending from said axis in the direction of the length of the shuttle, and a thread parter mounted on the lever arm and displaced rearwardly from the axis and in the direction of the length of the shuttle and positioned to engage the plate on the shuttle during the forward movement of the lay on a transfer-ring beat of the loom to part the weft.

14. In thread parting mechanism for a loom having a lay, a surface across which the weft extends carried forwardly by the lay, and a thread parter mounted and constructed to slide along the surface in contact with the weft to part the latter.

15. In thread parting mechanism for a loom having a lay, a surface carried forwardly by the lay and across which a weft thread extends, and a thread parter to slide along the weft and force the latter against the surface to part the weft.

16. In thread parting mechanism for a loom having a lay, a shuttle movable forwardly with the lay, a surface carried by the shuttle across which the weft extends, and a weft parter constructed and operated by forward motion of the lay to slide along the surface in contact with the weft to force

the latter against the surface and part said weft.

17. In thread controlling mechanism for a weft replenishing loom having a shuttle from which extends a weft thread, a pair of coacting weft parting elements one of which is carried by the shuttle, the other element being mounted for angular movement and movable angularly by contact with the shuttle carried element to be aligned with the latter, the filling extending across the shuttle carried element and being parted by a pinching action between the elements.

18. In thread controlling mechanism for a weft replenishing loom having a shuttle from which extends a weft thread, a pair of coacting weft parting elements one of which is carried by the shuttle, the other element mounted to move transversely of the weft, engagement of the elements causing said other element to move relatively to the element on the shuttle and transversely of the weft to sever the latter.

19. In thread controlling mechanism for a weft replenishing loom having a shuttle from which extends a weft thread, a lay to carry the shuttle forwardly during the act of transfer, a weft parting element mounted on the front wall of the shuttle, and a second thread parting element having a vertically extending edge to engage the first element and mounted to move relatively to the element on the shuttle, said second element so disposed that one end of the vertical edge will strike the first named element in advance of the other and cause alignment of said cutting edge with the first element.

20. In thread controlling mechanism for a weft replenishing loom having a shuttle from which extends a weft thread, a lay to carry the shuttle forwardly, a cutting element carried by the front wall of a shuttle and across which the weft extends, a second parting element, and a pivotal support for said second element, the latter having a vertical parting edge one end of which engages the shuttle carried element in advance of the other end, advance movement of the lay causing a relative vertical movement between the parting elements to effect contact of the whole length of the vertical cutting edge with the lay carried element.

21. In thread controlling mechanism for a weft replenishing loom having a shuttle from which extends a weft thread, a lay to carry the shuttle forwardly, a center around which the lay moves pivotally, and a pair of thread parting elements one of which is carried by the lay and has a surface transverse of the line of movement of the lay, the other element mounted independently of the lay to engage the element on the lay and move angularly while in contact therewith during the advance of the lay.

22. In thread controlling mechanism for a

weft replenishing loom having a shuttle from which a weft thread extends, a lay to carry the shuttle forwardly, a pivot around which the lay swings, a pair of cooperating thread parting elements one of which partakes of the arcuate movement of the lay as the same beats up, the second element being pivotally mounted independently of the lay to contact with and share the changing angular positions of the first named element as the lay beats up.

23. In thread controlling mechanism for a weft replenishing loom having a shuttle from which a weft thread extends, a lay to carry the shuttle forwardly, a pair of thread parting elements brought into cooperation by forward movement of the lay, said elements constructed and operated to have relative vertical and horizontal movements while in contact with each other and the weft during forward movement of the lay.

24. In a weft replenishing loom having a lay and a shuttle thereon with a thread delivery eye extending away from the adjacent selvage at the time of transfer, a cutter mechanism normally inoperative and including an element carried by the front wall of the shuttle adjacent the delivery eye, a thread clamping mechanism adjacent the end of the shuttle opposite the delivery eye, a weft detector to extend through the front wall of the shuttle, and transfer means to expel an exhausted bobbin from the shuttle, said transfer means effective upon a transferring beat of a loom 35 to control the cutter mechanism and also withdraw the detector to a position in front of the front wall of the shuttle and out of the path of the weft extending between the cutter mechanism and clamp.

25. In a weft replenishing loom having a lay and a shuttle thereon with a thread delivery eye extending away from the adjacent selvage at the time of transfer, a thread clamp adjacent one end of the shuttle, a thread parter adjacent the other end of the shuttle, a weft detector intermediate the ends of the shuttle to extend into the latter from a position in front of the shuttle, and means to actuate the clamp and withdraw the detector to a position in front of the weft extending between the cutter and clamp prior to the time of operation of the parter.

26. In a loom having a lay, a front shuttle box defining wall fast with respect to the lay to engage the front of the shuttle, a shuttle to be carried by the lay and located behind the wall, and cooperating thread parting members one of which is carried by the shuttle on the front face thereof and the other of which is independent of the shuttle, said members having weft parting engagement with each other under the wall.

27. In a weft parting device for a loom having a lay operating with a shuttle, the lay and shuttle advancing on transfer picks

of the loom, an anvil carried on an exterior advancing surface of the shuttle and substantially aligned with said surface, and a parting member to engage the anvil on transferring beats of the loom to part the weft. 70

28. In a weft parting device for a loom having a lay operating with a shuttle, the lay and shuttle advancing on transferring picks of the loom, a delivery eye located at one end of the shuttle the latter having a weft supply therein which extends from a point within the shuttle through the delivery eye toward the cloth, and cooperating elements one of which is carried by the shuttle and disposed along the path of the weft between the delivery eye and the cloth to co-act and part the weft at the time of transfer.

29. In a weft parting device for a loom having a lay operating with a shuttle, the lay and shuttle advancing on transferring picks of the loom, a delivery eye for the weft, and a pair of thread parting cooperating members one of which is carried by the shuttle on the front face thereof and in horizontal alignment with the delivery eye, said members effective to part the weft at the time of transfer.

30. In a weft parting device for a loom having a lay operating with a shuttle, the lay and shuttle advancing on transferring picks of the loom, the weft of the shuttle when the latter is in transfer position having the length extending away from the cloth, a delivery eye through which another length of the weft extends back toward the cloth, both of said lengths being disposed longitudinally of the shuttle and one in front of the other, and a pair of thread parting members one of which is carried by the shuttle to engage and part the front length of weft. 100 105

31. In a weft parting device for a loom having a shuttle provided with a delivery eye and having a supply of weft which when the shuttle is in transferring position is looped back on itself providing front and back portions, and a pair of coacting weft parting members one of which is carried by the shuttle to part the front portion of said weft. 110 115

32. In a loom having a lay and a shuttle thereon with a thread delivery eye extending away from the adjacent selvage, means to part the weft of the outgoing bobbin adjacent the eye, means to clamp the weft adjacent the other end of the shuttle, a weft detector located between the thread parter and the clamp and on the side of the clamping means remote from the selvage, and means to withdraw the weft detector on weft parting beats of the loom to a point substantially in advance of the weft extending between the cutter and clamp. 120 125 130

In testimony whereof I have hereunto affixed my signature.

OSCAR V. PAYNE. 130
